UNITED STATES PATENT OFFICE.

JOSEPH KOMOROUS, OF RIVERSIDE, ILLINOIS, ASSIGNOR TO PARISIAN NOVELTY COMPANY, OF CHICAGO, ILLINOIS.

THERMOMETER.

Application filed December 15, 1920. Serial No. 430,850.

To all whom it may concern:

Be it known that I, JOSEPH KOMOROUS, a citizen of the United States, and a resident of the city of Riverside, county of 5 Cook, and State of Illinois, have invented certain new and useful Improvements in Thermometers, of which the following is a specification.

My invention relates to improvements in 10 thermometers, and has for its object the provision of an improved construction of this character which is durable and efficient in use and capable of economical manufacture.

15 Other objects will appear hereinafter.

The invention consists in the combinations and arrangements of parts herein-after described and claimed.

The invention will be best understood 20 by reference to the accompanying drawings forming a part of this specification, and in which,

Fig. 1 is a face view of a thermometer construction embodying the invention.

25 Fig. 2 a section taken on line 2—2 of Fig. 1,

Fig. 3 a section taken on line 3—3 of Fig. 1,

30 Fig. 4 a section taken on line 4—4 of Fig. 2.

The preferred form of construction, as 35 illustrated in the drawings, comprises a facing sheet 5 of congealable gelatinous material such as celluloid. The sheet 5 is reinforced and stiffened by means of a backing 6 of sheet metal secured thereto. The sheet 5 carries on its outer face an ordinary thermometer tube 7 secured in place by means of metal loops or staples 8, having 40 their ends passed through the sheets 5 and 6 and upset or clinched at 9 against the inner face of the sheet 6 and thus serving as a simple and convenient mounting for the tube and also serving to hold the sheets 5 and 6 together. The outer face of the sheet 5 is also 45 provided with a suitable thermometer scale as shown, said scale being arranged in zig-zag form with alternate portions on opposite sides of the thermometer tube. The 50 mounting is further reinforced and stiffened by means of a sheet 10 of cardboard or the like, the sheets 5 and 6 being secured to the sheet 10 by first folding the edges 11 of the sheet 5 over the edges of the sheet

6 and then upsetting or bending said edges 55 around the edges of the cardboard sheet 10, as shown, and whereby the sheet 5 will be stretched and secured in place. The cardboard sheet 10 is provided in its upper edge with two adjacent notches 12 and a 60 support in the form of a string 13 is formed into a loop by tying a knot 14 between the ends thereof, said loop being inserted in the notches 12 as indicated, before the edges of the sheets 5 and 6 are upset around the 65 edges of the sheet 10, said loop being thus firmly and securely held in place by the upset edges. In this manner, a simple and convenient means is provided for suspending the thermometer on a nail or the like 70 driven into a wall or the like.

By this arrangement, a thermometer is provided in which the thermometer tube is mounted in a very simple and convenient manner on a facing of heat insulating material and whereby the thermometer will be subjected practically only to atmospheric changes. The specific form and arrangement of the parts set forth is a simple and effective one for the purpose and renders 75 80 the construction capable of very economical manufacture.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the 85 90 scope of the appended claims.

Having described my invention, what I claim as new and desire to secure by Letters Patent is:—

1. A thermometer mounting comprising a metallic backing member having its edges upset; and a sheet of congealable material secured to said backing member by having its edges turned over and under the edges 95 100 of said member.

2. A thermometer mounting comprising a backing member having its edges upset; a sheet of material disposed over said backing member and having its edges turned over and under the edges of said backing member; and a re-inforcing member disposed within the upset edges of said back- 105

ing member and holding said material in proper position.

3. A thermometer mounting comprising a backing member having its edges upset; a sheet of dried gelatinous material secured to said backing member by having its edges turned over and under the edges of said backing member; and a re-enforcing member disposed within said upset edges and additionally holding said gelatinous material in position.

4. A thermometer comprising a metallic backing member having its edges upset; a sheet of material secured to said backing member by having its edges turned over the edges of said member; a thermometer tube arranged upon the face of said sheet of material; loops surrounding said tube and having their inner ends projected through and clinched against said metallic backing member; and a re-enforcing member in the rear of said metallic member and disposed within said upset edges for holding the sheet of material in position.

5. A thermometer comprising a facing consisting of a sheet of dried gelatin, a sheet of metal, and a sheet of cardboard, the edges of the gelatin sheet being folded around the edges of said metal and the combined edges of said metal and gelatin sheet being upset around the edges of said cardboard; a thermometer tube arranged on said facing sheet, there being a scale formed on said gelatin sheet in operative relation with said

tube, and metal loops surrounding said tube and having their ends passed through said gelatin and metal sheets and clinched against the inner face of said metal sheet, substantially as described.

6. A thermometer comprising a facing 35 consisting of a sheet of dried gelatin, a sheet of metal, and a sheet of cardboard, the edges of said gelatin sheet being folded around the edges of said metal and the combined edges of said metal and gelatin sheet being 40 upset around the edges of said cardboard; a thermometer tube arranged on said facing sheet, there being a scale formed on said gelatin sheet in operative relation with said tube, and metal loops surrounding said tube 45 and having their ends passed through said gelatin and metal sheets and clinched against the inner face of said metal sheet; and a support consisting of a looped member secured to said thermometer, there being 50 notches in one edge of said cardboard sheet to receive said looped member and said looped member being placed in said notches and secured in place by the upsetting of 55 said edges, substantially as described.

In testimony whereof I have signed my name to this specification in the presence of two subscribing witnesses.

JOSEPH KOMOROUS.
